UNITED STATES PATENT OFFICE

99,632

DESIGN FOR A COMBINED AUTOMOBILE AND FOLDING WING MONOPLANE

Edward F. Wagner, Philadelphia, Pa.

Application August 13, 1935, Serial No. 58,102

Term of patent 3½ years

To all whom it may concern:

Be it known that I, Edward F. Wagner, a citizen of the United States, residing at Philadelphia, in the county of Philadelphia and State of Pennsylvania, have invented a new, original, and ornamental Design for a Combined Automobile and Folding Wing Monoplane, of which the following is a specification, reference being had to the accompanying drawing, forming a part thereof.

Fig. 1 is a side elevation of the combined automobile and folding wing monoplane showing my new design.

Fig. 2 is a top plan view thereof, and
Fig. 3 is a front elevation of the same.

I claim:

The ornamental design for a combined automobile and folding wing monoplane, as shown.

EDWARD F. WAGNER.
